UNITED STATES PATENT OFFICE.

WILLIAM H. PRINZ, OF AUSTIN, ILLINOIS, ASSIGNOR TO THE SALADIN PNEUMATIC MALTING CONSTRUCTION COMPANY, OF CHICAGO, ILLINOIS.

APPARATUS FOR DRYING MALT.

SPECIFICATION forming part of Letters Patent No. 657,788, dated September 11, 1900.

Application filed August 15, 1898. Serial No. 688,622. (No model.)

To all whom it may concern:

Be it known that I, WILLIAM H. PRINZ, a citizen of the United States, residing at Austin, in the county of Cook and State of Illinois, have invented certain new and useful Improvements in Apparatus for Drying Malt; and I do hereby declare the following to be a full, clear, and exact description of the invention, such as will enable others skilled in the art to which it appertains to make and use the same.

My invention relates to a novel construction in an apparatus for drying malt, the object being to provide a device of this description of simple and efficient construction and operation; and it consists in the features of construction and combinations of parts hereinafter fully described and claimed.

In the accompanying drawings, illustrating my invention, Figure 1 is a vertical longitudinal section of an apparatus for drying malt constructed in accordance with my invention, taken partially on the line 1 1 and partially on the line 3 3 of Fig. 2. Fig. 2 is a vertical transverse section of same on the line 2 2 of Fig. 1. Fig. 3 is a fragmentary vertical longitudinal section of same on the line 3 3 of Fig. 2. Fig. 4 is a detail sectional view, on an enlarged scale, on the line 4 4 of Fig. 5. Fig. 5 is a detail sectional view on the line 5 5 of Fig. 4. Fig. 6 is a fragmentary vertical transverse section of a modified form of construction on the line 6 6 of Fig. 7. Fig. 7 is a fragmentary vertical longitudinal section on the line 7 7 of Fig. 6.

One feature of my invention consists in providing what I term a "mixing-furnace" for a malt-drier—that is, a furnace in which air is heated and which during its passage through said furnace is mixed with cool air.

Another feature of my invention consists in providing a further mixing-chamber above said furnace in which the hot and cold air are allowed to thoroughly mix before entering the drying-chamber.

Another feature of my invention consists in so forming said mixing-chamber as to leave spaces beside the same to form receptacles for finished malt, thereby saving the construction of an extra floor for said drier and the expense and space incidental thereto.

Another feature of my invention consists in a special form of hopper for said receptacles, which has greater capacity than the ordinary hopper, thereby saving space, and which can be automatically unloaded at small expense.

In the drawings, A indicates the lower or heating chamber of the kiln; B, the furnace; C, the mixing-chamber above the furnace, and D the drying-room. Said furnace B comprises a plurality of firing-chambers 1, inclosed within four walls and arched over, as at 2. Above the grate 3 and below the arch 2 the side walls are provided with openings 4, leading to chambers 5, arched over, as at 6. The end walls of said chambers 5 are provided with openings controlled by blinds 7, which form fresh-air inlets. The outer side walls of said chambers 5 are provided with openings 8, leading to the chambers 9, which lead to said mixing-chamber C. Blinds 10, fitted in openings in the end walls of said chambers 9, admit fresh air to said chambers. Thus the hot air in passing from the firing-chambers 75 to the mixing-chamber takes a zigzag course, during which fresh air is mixed therewith. The end walls of said chambers 1, 5, and 9 coincide with the end walls of the furnace B, the side walls 11 of which terminate on a level 80 with the floor 12, which surrounds the upper end of said furnace and above which the air from said furnace is delivered. The end walls of said furnace are extended upwardly over said floor 12 and extended lengthwise on 85 said floor, as at 13, to the end walls 14 of the building, thus dividing said floor 12 into three compartments, of which the middle one forms said mixing-chamber C. Said mixing-chamber C is closed at its upper end by means of 90 a horizontal partition 15, mounted between said walls 13, adjacent their upper ends, and which is provided with valve-controlled openings 16 at intervals. Supported upon said walls 13 is a hood 17, which is adapted to prevent malt dumped from the drying-floors from falling on said partition 15 and leading it into the side compartments 18. Said walls 13 are provided with recesses 19 at intervals along their upper edges, which extend down 95 to said partition 15. Said recesses 19 form passages through which the air is adapted to

pass into the drying-room D. In each of said compartments 18 I provide a hopper 20, of oblong form, covering the entire area thereof. The walls of said hopper 20 are inclined as usual, but its bottom instead of terminating in one point forms a long trough, which is connected at intervals with a spiral conveyer 21 by means of spouts 22. In said bottom of said hopper are a plurality of right and left spiral conveyers 23, which convey the malt toward the spouts 22, said conveyers 23 being mounted on a shaft 24, journaled in bearings in the end walls of said hopper and receiving its motion from said conveyer 21 by means of pulleys 25 and 26 on both conveyer-shafts and the belt 27 passing through openings in the floor 12.

In Figs. 6 and 7 I have illustrated a slightly modified form of mixing-furnace which is provided alternately with firing and mixing chambers, the firing-chambers 1 being less in height than the mixing-chambers 5, so as to leave passages 28 above said firing-chambers between the upper ends of the mixing-chambers. The dividing-walls between the mixing and firing chambers are provided with openings 29 above said firing-chambers, thus causing the air to pass from the firing into the mixing chambers and thence into the spaces 30 28, from which it passes into the mixing-chamber C. By means of this construction I am enabled to provide both a sufficiently-large mixing-chamber and hopper-floor without providing an extra floor, as heretofore, thus saving the cost of said extra floor and the extra height of building which would be required in consequence of said extra floor. I am also enabled to better regulate the temperature of the air admitted to the drying-chamber.

I claim as my invention—

1. In an apparatus for drying malt, the combination with a furnace having a firing-chamber mixing-chambers beside same through which the air from said firing-chamber passes means for admitting hot air to said mixing-chambers to be mixed with fresh air, of a mixing-chamber above said furnace adapted to receive the hot and fresh air from said furnace and mixing-chambers and further mix the same, substantially as described.

2. In an apparatus for drying malt, the combination with a furnace, and a floor surrounding it adjacent its upper end, of walls dividing said floor into a plurality of compartments, one of which communicates with said

furnace and is covered and the remainder of which are provided with hoppers adapted to receive finished malt, and means for unloading said hoppers comprising spiral conveyers 60 in the bottom thereof adapted to convey the malt to spouts leading from said hoppers, substantially as described.

3. In an apparatus for drying malt, the combination with a furnace, of a floor surrounding the upper end of same, partitions dividing said floor into a plurality of compartments, one of said compartments being adapted to receive hot air from said furnace and distribute same, and the remainder being 70 adapted to serve as malt-receptacles, substantially as described.

4. In an apparatus for drying malt, the combination with a furnace, of a floor surrounding the upper end of same, partitions dividing said floor into a plurality of compartments, one of said compartments being adapted to receive hot air from said furnace and distribute same, and the remaining compartments being adapted to contain hoppers, 75 substantially as described.

5. In an apparatus for drying malt, the combination with a furnace, of a floor surrounding the upper end of same, partitions dividing said floor into a plurality of compartments, one of said compartments being adapted to receive hot air from said furnace and distribute same, and the remaining compartments being adapted to contain hoppers, each of said hoppers covering the entire area of 90 the compartment in which it is situated, and provided in its bottom with conveyers, and with spouts leading therefrom, said conveyers being adapted to convey the malt to said spouts to discharge the same.

6. In an apparatus for drying malt, a floor divided into a plurality of chambers, constituting hot-air and malt-receiving chambers respectively, said malt-receiving chambers being adapted to contain one hopper each 100 covering the entire area thereof and provided in its bottom with right and left spiral conveyers adapted to convey the malt toward spouts connecting said hopper with devices for transporting the malt from said drier, substantially as described.

In testimony whereof I affix my signature in presence of two witnesses.

WILLIAM H. PRINZ.
